UNITED STATES PATENT OFFICE.

JOHN SPOUSTA, OF RIVER ROUGE, MICHIGAN.

FURNACE.

Application filed December 28, 1925. Serial No. 77,936.

My invention relates to a new and useful improvement in a furnace of the steam or hot water type. It is an object of the present invention to provide a furnace of this class, in which the heating fluid, whether it be water or steam, may be conducted to inner compartments for superheating, so that the heating fluid, when passing from the boiler is of a higher temperature than would ordinarily be the case were not the inner compartments used.

Another object of the invention is the provision of a boiler of this class, which will be simple in structure, economical of manufacture and highly efficient in use.

Another object of the invention is the provision of a boiler of this class, constructed from a plurality of interchangeable sections, so that the boiler may be constructed of any desired number of sections and thus its capacity regulated.

Other objects of the invention will appear as the description proceeds, these objects relating to the special type of sections and construction generally.

The invention consists in the combination and arrangement of parts hereinafter described and claimed.

The invention will be best understood from a reference to the accompanying drawings, which form a part of this specification and in which,

Fig. 1 is a side elevational view of the invention,

Fig. 2 is a sectional view taken on substantially line 2—2 of Fig. 4,

Fig. 3 is a sectional view taken on substantially line 3—3 of Fig. 4,

Fig. 4 is a vertical central sectional view of the invention,

Fig. 5 is a fragmentary sectional view taken on substantially line 5—5 of Fig. 4,

Fig. 6 is a fragmentary sectional view taken on substantially line 6—6 of Fig. 3,

Fig. 7 is a fragmentary view taken on substantially line 7—7 of Fig. 4.

As shown in the drawings, the invention comprises a base 15, upon which is adapted for mounting the lowermost section 16 having a water compartment 17 therein, with which communicates an inlet port 18 and a return port 19, the base 15 having a flange 20 for engaging the periphery of the section 16. The section 16 is provided, at its upper edge, with an outwardly projecting bead or flange 21, which is adapted to engage the periph-

ery at the lower edge of the section 22, which is formed with a chamber 23 and provided, at its upper end, with an outwardly projecting bead or flange 24. Mounted on the section 22 is a similar section 22' having the chamber 23' and the flange 24'. It will be noted that the section 22' is a duplicate of the section 22, any desired number of these sections being used, depending upon the capacity of the boiler desired to be constructed. Mounted on the upper section 22' is an arcuate dome 25 having a chamber 26 formed therein. The upper wall 29 of the section 16 is provided with a plurality of openings 29' which register with openings formed in the base 28' of the section 22, so as to establish communication between chambers 17 and 23. Similar openings 27 are formed in the upper wall 28 of the section 22 and communicate with openings formed in the base of the section above. The base of the dome is also provided with openings for establishing this communication, so that the chambers 17, 23, 23' and 26 are all in communication with each other.

Projecting inwardly in the chamber 17 from the inner surface of the side walls thereof are bosses 30 and 31, which are spaced apart sufficiently to permit the passage of a bolt head 33, which is mounted on the bolt 32 therebetween. When the bolt head 33 is passed between the bosses 31 and 30, so as to be positioned below the same, the head 33 may then be turned to engage the undersurfaces of the bosses 31 and 30, the head 33 being formed preferably rectangular, and of less width than its length, to permit this arrangement. The retaining bolts 32 are projected through the registering openings formed in adjacent top walls and bottom walls of adjacent sections and project through the dome, as clearly seen in the drawings. A nut 34 is threaded on the bolts 32, so that these bolts serve to retain the various sections in properly mounted position. The chamber 17 communicates through the inwardly projecting conduits 35, 36, 37 and 38 with a centrally disposed cup-shaped member 39, projecting upwardly from which is a flange 40. Positioned over this cup-shaped member 39, concentrically thereof, is an annular member 41 having a chamber 41' therein. The chamber 41' communicates through the inwardly projecting conduits 42 with the centrally disposed cylindrical container 43, which is open at both

ends. The interior of this container 43 is of the same diameter as the diameter of the flange 40. Projecting upwardly from the section 41, around the annular portion 43, 5 is a flange 46. As shown in Fig. 4, a flange 44 projects inwardly of the conduits 42 and a cylindrical sleeve 44' is pressed into the cylindrical flange 40 and the flange 44, so as to afford a water tight connection. The 10 section positioned on the section 41 is a duplicate of the section 41, the cylindrical sleeve 47 being pressed into the cylinder forming flange 46 and the cylinder forming flange 44 to provide an air tight connection. 15 A similar cylindrical sleeve 47 serves to communicate the upper section 41 with the interior of the dome or chamber 26, this sleeve 47 being pressed into the cylinder forming flange 46 and into the cylinder forming flange 48, which projects from the lower surface of the dome 25. Extending across the cup-shaped member 39 is a metal rib 50, preferably cast integral with the cup-shaped member 39, said member 50 being provided 20 with a centrally positioned opening in registration with an opening formed in the spider 51, which is mounted on the dome 25 in the chamber 26. Projected through these openings is a bolt 52 provided with a nut 52', 25 upon the threading of which the sections are bound tightly together. An outlet 53 is formed in the dome to which suitable piping may be attached for conducting the steam or hot water from the dome. Formed 30 in the dome 25 and communicating with the space surrounded by the sections 16, 22 and 22' is a flue opening 55 over which may be mounted suitable piping.

In the form shown in Fig. 4, the invention is constructed for use with an oil burner. It is evident, however, that if desired any form of fuel may be used, the grates being suitably supported within the section 16, adjacent the lower end thereof. The specific 45 mounting of the grating is a detail of structure which forms no part of the present invention, and consequently, is not shown.

It is believed evident from the description that the water or steam, when passing from the chamber 17, into the chamber 41' of the sections 41, will be subjected to the hot gases arising from the fire box and the steam or water heated to a higher temperature than is the water in the chambers 17, 23 and 23'. 50 The interchangeability of the parts is also believed apparent, as well as the durable and compact structure which is provided.

With such a structure, the boiler and its various parts may be formed entirely from 55 castings which are easily assembled in operative position and in which a minimum number of machined parts is used.

While I have illustrated and described the preferred form of structure, I do not wish 60 to limit myself to the precise form of struc-

ture shown, but desire to avail myself of such variations and modifications as come within the scope of the appended claims.

Having thus described my invention what I claim as new and desire to secure by Letters Patent is:

1. A furnace of the class described comprising a plurality of superimposed sections each of said sections being formed substantially cylindrical and double walled to provide a chamber, the ends of said chamber in each of said sections being closed and the chambers in adjacent sections communicating through aligning openings formed in the end closures; a dome mounted on the uppermost of said sections having a chamber communicating with the chamber of the section below it; and stay rods projected through said aligning openings for binding said dome and said sections in co-operative relation; a plurality of double walled superimposed drums positioned within said assembled sections having their periphery spaced slightly from the inner surface of said sections, each of said drums being provided with a central cylindrical passage and a chamber extending around the inner surface of the outer walls; a plurality of conduit means for communicating said chamber in said drum with said central passage and means for communicating the central passage of the lowermost of said drums with the chamber of the lowermost of said sections, the central passage of each of said drums being in communication with each other and with an outlet port formed in said dome. 95

2. A furnace of the class described comprising a plurality of superimposed sections each of said sections being formed substantially cylindrical and double walled to provide a chamber, the ends of said chamber in each of said sections being closed and the chambers in adjacent sections communicating through aligning openings formed in the end closures; a dome mounted on the uppermost of said sections having a chamber communicating with the chamber of the section below it; and stay rods projected through said aligning openings for binding said dome and said sections in co-operative relation; a plurality of double walled superimposed drums positioned within said assembled sections having their periphery spaced slightly from the inner surface of said sections, each of said drums being provided with a central cylindrical passage and a chamber extending around the inner surface of the outer walls; a plurality of conduit means for communicating said chamber in said drum with said central passage; means for communicating the central passage of the lowermost of said drums with the chamber of the lowermost of said sections, the central passage of each of said drums being in communication with 100 each other and with an outlet port formed in said dome. 110

each other and with an outlet port formed in said dome, and means projected through said central passage for binding said sections and said drums in co-operative relation.

3. A furnace of the class described comprising a plurality of superimposed sections, each of said sections being double walled to provide a chamber; walls on each of said sections for closing said chambers, the chambers of adjacent sections being in communication with each other through aligning openings formed in said end walls; an inverted cup-shaped member mounted axially of the lowermost of said sections; conduit means for communicating said cup-shaped member with the chamber of said section; a plurality of drums mounted in said sections in superimposed relation, each of said drums being provided with a central passage in communication with said cup-shaped member and each of said drums being double walled to provide a chamber; means for communicating said chambers of said drums with said central passage; a rib mounted in said cup-shaped member; a dome mounted on the uppermost of said sections, said dome having a peripheral chamber in communication with the chambers of said sections and provided with an outlet opening communicating with said central passages; a spider on said dome; a stay rod connecting said spider and said rib for retaining said drums and said sections in assembled relation; stay rods projected through the aligning openings of said sections for binding said sections in co-operative relation.

4. A furnace of the class described comprising a plurality of superimposed sections, each of said sections being double walled to provide a chamber; walls on each end of said sections for closing said chambers, the chambers of adjacent sections being in communication with each other through aligning openings formed in said end walls; an inverted cup-shaped member mounted axially of the lowermost of said sections; conduit means for communicating said cup-shaped member with the chamber of said section; a plurality of drums mounted in said sections in superimposed relation, each of said drums being provided with a central passage in

communication with said cup-shaped member and each of said drums being double walled to provide a chamber; means for communicating from said chambers of said drums to said central passage; a rib mounted in said cup-shaped member; a dome mounted on the uppermost of said sections, said dome having a peripheral chamber in communication with the chambers of said sections and provided with an outlet opening communicating with said central passages; a spider on said dome; a stay rod connecting said spider and said rib for retaining said drums and said sections in assembled relation; stay rods projected through the aligning openings of said sections for binding said sections in co-operative relation; a sleeve for effecting a water tight connection between said cup-shaped member and the central passage of the lowermost of said drums; a sleeve for effecting a water tight connection between the central passage of adjacent drums; and a sleeve for effecting a water tight connection between the outlet opening of said dome and the central passage of the uppermost of said drums.

5. A furnace of the class described comprising a plurality of superimposed sections, each of said sections being double walled to provide a chamber; a plurality of double walled superimposed drums positioned within said assembled sections, having their peripheries spaced slightly from the inner surface of said sections, each of said drums being provided with a central cylindrical passage, and a chamber extending around the inner surface of the outer walls of said drums; a plurality of conduit means for connecting said chambers in said drums in communication with said central passage; and means for connecting the central passage of the lowermost of said drums to the chambers of the lowermost of said sections, the chambers in said sections being in communication with each other, the central passages of said drums being in communication with each other and with an outlet port.

In testimony whereof, I have signed the foregoing.

JOHN SPOUSTA.
